UNITED STATES PATENT OFFICE.

WILLIAM VOSS, OF WILMINGTON, DELAWARE, ASSIGNOR TO AMERICAN CAR & FOUNDRY COMPANY, OF ST. LOUIS, MISSOURI, A CORPORATION OF NEW JERSEY.

CAR-TRUCK.

SPECIFICATION forming part of Letters Patent No. 789,511, dated May 9, 1905.

Application filed February 20, 1905. Serial No. 246,462.

To all whom it may concern:

Be it known that I, WILLIAM Voss, a citizen of the United States, residing at Wilmington, Newcastle county, Delaware, have invented a certain new and useful Improvement in Car-Trucks, of which the following is a full, clear, and exact description, such as will enable others skilled in the art to which it appertains to make and use the same, reference being had to the accompanying drawings, forming part of this specification, in which—

Figure 1 is a top plan view of a portion of my improved car-truck. Fig. 2 is a side elevational view of the same, and Fig. 3 is a sectional view through one of the side frames.

This invention relates to a new and useful improvement in car-trucks designed especially for use in connection with electric motors, the object being to construct a truck of the character described with a short wheel-base and a minimum height of frame.

By my improved construction a minimum height of the frame is obtained by locating the spring to one side of the journal-boxes instead of over the journal-boxes, as is usually practiced. A low frame so produced is very desirable in both open and closed cars, as it permits the use of a single step to the car.

With these objects in view the invention consists in the construction, arrangement, and combination of the several parts of my device, all as will be hereinafter described and afterward pointed out in the claims.

In the drawings the side frame of the truck consists of a top bar 1, bent at its ends, said ends being connected by end angles 2.

3 indicates a spring-supported motor suspension-bar which is preferably bent so as to carry the motors outside of the axles, the bent portion of this bar providing the necessary room for such suspension.

4 indicates the bottom bar of the side frame, which is secured at its ends to the bent ends of the top bar 1.

5 indicates the end casting, to which the transom members 6 are secured, said end casting serving practically as a strut for the trussed side frame, of which the top bar 1 is the compression member and the bottom bar 4 is the

tension member. The transoms 6 are provided with suitable bearings 7, in which are mounted links 8, supporting the spring-plank 9. Between the links 8 this spring-plank carries the bolster-supporting springs 10, preferably elliptical springs, on which is carried the bolster 11, said bolster having the usual side and center bearings and being of ordinary construction.

12 indicates a connection-plate riveted to the top bar 1 and having inwardly-extending portions riveted to the transom members 6.

The end casting or strut 5 forms a support for the inner ends of arms 13, which are pivotally connected thereto. These arms 13 carry the journal-boxes 14, in which the wheel-axles 65 are mounted. The outer ends of arms 13 are provided with spring-seats 15, in which are arranged springs 16, bearing at their upper ends against appropriate seats 17, secured to the top bar 1.

18 indicates guide-plates arranged on the free ends of arms 13, said guide-plates co-operating with rubbing-plates 19 on the inner faces of the bent portions of the bar 1.

When the car-body is supported by the bolster 11, its load is transmitted through the springs 10 onto the transoms 6 and thence to the side frames. The links 8 accommodate the lateral swaying movement of the car-body, this construction being well known in what are commonly termed "swing-motion" trucks. The arms 13 being pivoted to the end casting 5 will yieldingly support the load through the springs 16, whose vertical movement is guided by the plates 18, as will be readily understood.

It will be observed that the springs are arranged outside of the axles, thus enabling the truck-frame to be lowered, the pivotal connection of the arm to the strut improving the spring action. The location of the springs outside the journal-boxes also enables the use of springs of greater height than is possible if said springs were arranged above the boxes, and in addition the distance between the springs is greater than the distance between the axles, which contributes to the steadiness of the frame in service, particularly under those conditions where the forces are applied

first to one end and then the other by the kick or reaction of the motors or by the application of the brakes, which latter, however, is not so considerable.

5 I am aware that changes in the construction, arrangement, and combination of the several parts of my device can be made and substituted for those herein shown and described without in the least departing from the nature 10 and principle of my invention.

Having thus described the invention, what is claimed as new, and desired to be secured by Letters Patent, is—

15 1. In a car-truck, the combination with a compression member whose ends are bent so as to provide vertical faces, a tension member, a strut, and journal-boxes pivotally connected to the strut and guided in their vertical movements by the vertical faces of the compression 20 member; substantially as described.

25 2. In a car-truck, the combination with a bar 1 bent at its ends, an end casting, a bar 4 secured to said end casting and to the bent ends of said bar 1, journal-boxes pivotally connected to said end casting, means for guiding said vertical boxes in their vertical movement, and springs for cushioning the vertical movement of said journal-boxes; substantially as described.

30 3. In a car-truck, the combination with a side frame, of journal-boxes pivotally mounted upon said frame, means for guiding the free ends of said journal-boxes in their vertical movement, and springs arranged to one side 35 of said journal-boxes; substantially as described.

40 4. In a car-truck, the combination with a trussed side frame, of journal-boxes pivotally connected to the strut of said trussed side frame, means for guiding the free ends of said

journal-boxes, and springs arranged to one side of said journal-boxes; substantially as described.

5. In a car-truck, the combination with a side frame, of arms 13 pivotally mounted thereon, journal-boxes carried by said arms, means for guiding the free ends of said arms, and springs coöperating with said arms, said springs being arranged adjacent the free ends of the arms; substantially as described. 45

6. In a car-truck, the combination with a trussed side frame whose compression member is bent to provide guideways at its ends, arms pivotally connected to the strut of said side frame, journal-boxes carried by said arms, the free ends of said arms coöperating with said guideways, spring-seats on the arms, and springs interposed between said seats and the compression member; substantially as described. 55

7. In a car-truck, the combination with a trussed side frame, of arms pivotally connected to the strut of said trussed side frame, journal-boxes carried by said arms, springs coöperating with said arms outside the journal-boxes, the free ends of said arms being guided by a member of the trussed side frame, and motor-supporting bars yieldingly carried by the ends of said trussed side frame, said motor-bars being offset to enlarge the distance between the same and the truck-axles; substantially as described. 65

In testimony whereof I hereunto affix my signature, in the presence of two witnesses, this 15th day of February, 1905.

WILLIAM VOSS.
